UNITED STATES PATENT OFFICE

WILLIAM D. LOUGHLIN, OF BOONTON, NEW JERSEY

RADIO SIGNALING CIRCUIT

Application filed March 5, 1925. Serial No. 13,249.

(GRANTED UNDER THE ACT OF MARCH 3, 1883, AS AMENDED APRIL 30, 1928; 370 O. G. 757)

My invention relates broadly to radio receiving circuits and more particularly to radio compass receiving circuits.

The object of my invention is to provide an economic and efficient means for tuning the loop circuit of a radio compass system over a very broad band of frequencies.

Further objects of the invention will appear more fully hereinafter.

10 The invention consists substantially in the construction, combination, location, and relative arrangement of parts and circuit arrangements associated therewith, as will be more fully hereafter set forth, as shown by 15 the accompanying drawings and finally pointed out in the appended claim.

Reference is to be had to the accompanying drawings forming a part of this specification in which like reference characters indicate 20 corresponding parts throughout the several views and in which Figure 1 represents the preferred embodiment of my invention and

Figure 2 shows a modification in which the shunted inductance is made variable and in 25 which the variable tuning condenser as is used in the conventional radio compass circuits, may be fixed.

In the conventional radio circuit, comprising a fixed coil and associated variable condenser the tuning ratio, (maximum to minimum wavelength or frequency) is of the order of two and one-half to one, (2½:1) and only by skillful disposition of connecting leads to reduce the residual capacities is it 35 possible to extend the tuning range to a three to one (3:1) ratio.

The present practice of increasing the width of the band of frequencies to which a radio compass will respond is either to add 40 inductance in series with the collector system or provide a switching arrangement to short circuit or cut out turns in the collector system or to add capacity in parallel with the tuning capacity. The advantages of my invention 45 will be understood by those familiar with the art when consideration is given to the fact that the reception factor or the efficiency reception of a radio compass system is directly proportional to the area enclosed by the coil system 50 and the number of turns and is inversely pro-

portional to the radio frequency resistance and the total shunt capacity. When the method of adding inductance in series with the loop system is used, the area and number of turns of the loop system is limited to a 55 value such that when the series inductance is short-circuited the system will respond to the shortest contemplated wavelength; any increase in wavelength range requires inductance in series thereby increasing the high frequency resistance of the circuit. Besides this, the added inductance does not increase the coupling with the flux of the observed wave. Furthermore, adding inductance in series 60 will cause the collector system to become electrically unsymmetrical and will require a compensating device for the collector system to indicate the true direction of the propagated wave. It is possible to add inductance in each lead of the collector system but such 65 means will require a most careful selection of inductance and a most complicated switching arrangement and usually requires a variable compensating device. Short circuiting or opening turns of the loop system introduces a 70 dead-end effect of the turns thus eliminated and unless complicated switching arrangements are used the electrically symmetry of the loop is destroyed and compensators are required. Adding capacity in parallel with 75 the tuning capacity decreases the efficiency of the system as the voltage variation delivered to the receiver or amplifier depends upon the inductance capacity ratio. The larger the capacity the smaller the voltage variation. 80

My invention provides means for avoiding the disadvantages outlined above and is based upon the principle that the resultant inductance of two inductances connected in parallel is directly proportional to their product and 85 inversely proportioned to their sum. By adding an inductance in parallel with the loop system the tuning range of the loop system is shifted to a different band of wavelengths or, by adding a variable inductance in parallel 90 and keeping the capacity of the loop system constant, the loop system may be tuned by the variable inductance. In both cases the electrical symmetry of the loop system is not destroyed. The inductance of the closed reson- 95 100

ant system, and hence the wavelength of the loop system, is varied by varying an inductance connected in parallel with the loop circuit.

5 Referring more particularly to Figure 1 numeral 1 represents the loop circuit of a radio compass system and 2 represents the tuning condenser. Between the terminals of 1 and 2 and in parallel with 1 and 2 is connected 10 one of a plurality of fixed inductances, 4 and 5, (two are shown in this disclosure but a greater number may be used). 3 represents the out-put terminals for connecting 1 and 2 and the associated inductance to a receiver 15 and amplifier. The inductances 4 and 5 are mounted in the operating room in close proximity to the tuning condenser 2 and are shielded from the loop turns 1. There is, therefore, no mutual inductance between the 20 inductances 1 and 4 or 1 and 5. The selection of any one individual shunt inductance is to be had by a suitable switching arrangement 6. This switching arrangement should be one having a low distributed capacity.

25 The radio compass loop system is tuned over a definite band of frequencies the shunt inductance 4 is connected in parallel with 1 by the switching arrangement 8 and tuning accomplished by varying the condenser 7. A 30 third definite band of frequencies is provided for by the selection of a shunt inductance coil 5 of a different inductance value. The selection of these or other shunt inductances may be such that a continuous and very broad 35 band of frequencies, with suitable overlaps if desired, is available.

Figure 2 shows the modification of this invention in which the shunt inductance 4 is made variable over large values of inductance. 40 Tuning may be accomplished in this case by varying the inductance 4 and keeping the condenser 2 fixed.

45 It will be understood that the above description and accompanying drawings comprehend only the general and preferred modification of the invention and that various minor changes in detail of construction, proportion and arrangement of parts may be within the scope of the appended claim and 50 without sacrificing any of the advantages of my invention.

The invention herein described may be manufactured and used by or for the Government of the United States for governmental 55 purposes without the payment to me of any royalty thereon or therefor.

Having described my invention I claim:

60 In a radio compass system, the combination of a closed loop circuit susceptible to the electromagnetic component of an incoming wave, a plurality of separate inductance coils of differing values of inductance, means for shielding said coils from said closed loop circuit, means for individually connecting said 65 coils in parallel with said loop circuit, a con-

denser in parallel with said closed loop circuit and said connecting means, and means for coupling said radio compass system to a receiver.
